CLAIM

The ornamental design for an asymmetrical electrical connector, as shown and described.

DESCRIPTION

This application is related by subject matter to U.S. patent application Ser. No. 29/334,906 entitled “Asymmetrical Electrical Connector” filed on even date herewith.

FIG. 1 is a top, left, rear perspective view of an asymmetrical electrical connector according to our design;

FIG. 2 is a rear elevation view thereof;

FIG. 3 is a top plan view thereof;

FIG. 4 is a right side elevation view thereof;

FIG. 5 is a bottom plan view thereof;

FIG. 6 is a left side elevation view thereof; and,

FIG. 7 is a front elevation view thereof.

The broken line in the figure drawings is included to show the environment of unclaimed subject matter only and forms no part of the claimed design. The dash-dot line represents the boundary of the claimed design.

In a preferred embodiment, the nature of this product is an electrical connector in the form of an electrical connector housing configured for retaining a plurality of electrical contacts.
